CARRYING MECHANISM FOR CALCULATING MACHINES

John Carlsen, Hellerup, by Copenhagen, Denmark

Application October 14, 1946, Serial No. 703,247
In Denmark October 18, 1945

1 Claim. (Cl. 235—137)

1

The present invention relates to the carrying mechanism of calculating machines of the kind in which the number wheels are turned by depressing the amount keys, and in which the calculating unit for the numerals of each denomination, with the exception of the highest, comprises a carrying member which, in the case of a calculating operation in the unit in question requiring a carrying operation, is released so as to be permitted to perform a carrying movement.

If in calculating machines of this kind, keys belonging to two neighbouring calculating units are simultaneously depressed, as is particularly the case when such machines are employed for multiplication, it may occur that, while an addition is taking place in the calculating unit of the higher order under the influence of the depression of a key belonging to such calculating unit, a carry transfer to this calculating unit is at the same time initiated from the calculating unit of the lower order as a consequence of a key belonging to the latter being depressed. If the two impulses thus created for turning the number wheel of the calculating unit of the higher order happen to overlap in time, an error in calculation may occur, because in the overlapping period no addition will take place of the movements of the number wheel which each of the two impulses, if acting alone, would be capable of creating.

To avoid the possibility of such errors, it has been proposed to provide each calculating unit, to which a carry transfer may take place from a calculating unit of lower order, with a transfer lock adapted to prevent the possibility of a carry transfer to the calculating unit in question, as long as a calculating operation is taking place within such calculating unit on account of the depression of a key in the row of keys belonging to same. The transfer lock is constructed in such a manner that on the depression of any key belonging to the calculating unit in question—for the purpose of the following specification to be referred to as the receiving calculating unit as distinguished from the initiating calculating unit, i. e. the calculating unit of the next lower denomination which initiates the carrying operation—it is caused to assume a locking or barring position preventing the carrying member of the initiating calculating unit from performing its carrying movement. Accordingly, the carrying operation cannot take place until the transfer lock has been moved from the said barring position to a releasing

2

position, which takes place only when the depressed key of the receiving calculating unit has been released and has returned to its normal position.

The present invention is based on the recognition that the employment of a transfer lock on these lines does not afford full security against the overlapping of an operation of simple addition within a calculating unit and a carry transfer to same. The fact is that the transfer lock is moved to its locking position, only when a key of the receiving calculating unit is depressed, and hence, a perceptible amount of depression movement is necessary before the transfer lock becomes effective, and if now the carry transfer from the initiating calculating unit should take place before the said amount of the depression movement has been completed, the above mentioned error may occur. It might seem possible to obtain security against this error by arranging for the amount of depression necessary in the receiving calculating unit in order to bring the transfer lock into action to be smaller than the smallest amount of depression in the initiating calculating unit capable of initiating the carrying operation, but as a matter of fact no real security is obtained in this manner, because two simultaneously depressed keys of the receiving and the initiating calculating unit respectively are not synchronized in their movements, but are depressed by means of individual fingers, so that, under unfavourable conditions, it may occur that the key of the initiating calculating unit is far advanced in its depression movement relatively to the key of the receiving calculating unit.

This kind of error in calculation will of course be very rare, indeed such that it will hardly be possible to reproduce such an error if it is ascertained. But that is particularly why such an error is to be considered extra grave, because the operator will then be inclined to satisfy himself in the belief that he has pressed the wrong key the first time, or perhaps he will send the machine to a service agency for inspection without the latter being capable of bringing to light the reason why the error came about.

The present invention has for its purpose to eliminate this drawback, and this is obtained by arranging for the initiating calculating unit to control the transfer lock. According to my invention the carrying operation does not take place until the depressed key of the initiating calculating unit has practically returned to its original position. Thus there is no possibility

of a depression of a key of the receiving calculating unit being in train, for although two fingers need not necessarily be in full synchronism when simultaneously depressing keys of the receiving and the initiating calculating units respectively, it will easily be understood that one finger cannot possibly be moving upwards, while the other finger is moving downwards.

Further details of the invention will appear from the following description of an embodiment of the invention as applied to a five key calculating machine, i. e. a machine of the type having keys only for the numerals 1-5 in each column, the addition of the higher numerals being effected by striking twice, e. g. 2×3 instead of 6, 3+4 instead of 7 etc. Reference will now be had to the accompanying drawings in which

Fig. 1 shows a calculating unit representing the numerals of one order in a calculating machine provided with carrying mechanism according to the invention, as viewed in side elevation, and

Fig. 2 shows the same in plan view.

There are five key arms 11-15, each carrying a key representing the numerals 1-5 respectively. Of these keys only the key 5 representing the amount "5" is shown in the drawing. The key arms 11-15 are arranged in juxtaposed relationship so as to form a fan-like structure, and all the key arms are pivotable on a common pivot 16. The key arm 15 is provided with a stud 17 engaged in elongated slots 18, 19, 20 and 21 of the key arms 11, 12, 13 and 14, so that on the depression on any of the keys fixed to the key arms 11-15, the key arm 15 will be swung downwards on the pivot 16. The angle through which each key arm 11-15 is depressed until striking the base of the machine as represented at 50 will be proportional to the number represented by the key in question, and since each of the key arms 11-14 on being depressed carries with it the key arm 15 through its entire stroke, the angle through which the key arm 15 is moved will always be proportional to the number represented by the depressed key. The detailed construction of the key system is the subject matter of my co-pending application No. 628,698, filed on November 15, 1945, now U. S. Letters Patent No. 2,472,519, and has no direct bearing on the present invention, so that a further description is considered unnecessary for the purposes of the present specification.

The key arm 15 carries a toothed sector 22, which by means of a gear wheel and a ratchet drive operates a number wheel 24 in such a manner that on the depression of any key the number wheel will be advanced through an angle corresponding to the number represented by the depressed key, such turning of the number wheel taking place simultaneously with the depression of the key. A pawl 25 co-operating with teeth 26 of the number wheel serves to brake the number wheel and to arrest it in its prescribed positions.

The number wheel 24 cooperates with a carrying member 27 serving to carry forward one to the calculating unit of the next higher order when the number wheel 24 passes through the "zero" position. The carrying member 27 is pivoted at 28 and is loaded by a spring 31 tending to turn it in an anticlockwise direction. Thus, when not subjected to other influences the carrying member will not be in the position shown in Figs. 1 and 2, but in a position swung so far in an anticlockwise direction that an abutment 45 carried by the carrying member is in contact with the

edge 43 of a hole 44 in the partition 41 between the considered calculating unit and the calculating unit of the next higher order. The carrying member 27 is provided with a toothed sector 29 adapted to cooperate with a number of projecting teeth 30 on the end surface of the number wheel 24. The lowermost tooth 29a of the toothed sector 29 is bent out of the overall plane of the toothed sector in the direction towards the number wheel 24, while the other teeth 29b, 29c and 29d of the toothed sector are bent out of its plane in the opposite direction. Similarly the leading tooth 30a among the teeth 30 of the number wheel is lower as measured in the axial direction than the other teeth 30b, 30c and 30d. By this means it follows that the teeth 29a and 30a will intermesh the plane A, Fig. 2, rather than the plane B in which the teeth 29b, 29c and 29d mesh with the teeth 30b, 30c and 30d.

The characteristic feature of the invention is represented by a transfer lock in the form of a U-shaped barring member 32, the body 33 of which rests on the top edge of the key arm 15, while with its shanks 34 and 35 it is rotatably mounted on a pin 36. A torsional spring 37 tends to keep the body 33 of the barring member in constant contact with the key arm 15. The shank 35 of the barring member 32 is provided with a detent 38 co-operating with the back of the toothed sector 29. Each time the key arm 15 is depressed, the said detent 38 is moved towards the back of the toothed sector 29 under the influence of the spring 37. As long as the carrying member 27 has not yet been turned to its position of release, i. e. the position in which it is released by the teeth 30 of the number wheel 24, the said movement of the detent 38 towards the back of the toothed sector 29 will be without effect, but immediately before the carrying member 27 comes into the position of release, the detent 38 will be capable of snapping in behind a shoulder 39 provided at the back of the toothed sector so as to keep the carrying member 27 barred or locked in the position of release, until the detent 38 on the barring member 32 is again moved toward the left, which takes place only when the key arm 15 has been practically restored to its normal position.

Thus, it will be realized that the barring member 32 has the effect that no carry transfer to the calculating unit of the next higher order, i. e. the receiving calculating unit, can take place during the initiating calculating operation in the calculating unit shown, i. e. the initiating calculating unit, but only after the calculating operation has been completed and the depressed key has practically returned to its original position. In other words, the barring member 32 forms a transfer lock which is controlled by the initiating calculating unit.

All the parts so far described belong to the calculating unit of one order, and in the embodiment shown are situated in the space between two partitions 40 and 41. As will be understood, any number of calculating units may be provided at both sides of the one shown. 27' is a carrying member exactly similar to the carrying member 27, but belonging to the calculating unit of the next lower order of which no other details are shown. The carrying member 27' has pivoted to it a pawl 42' engaging with the teeth 26 for the purpose of transfer to the number wheel 24 from the calculating unit of the next lower order. It will be understood that the carrying member 27 is provided with a pawl (not shown) exactly

similar to the pawl 42' for the purpose of transfer from the calculating unit shown to the calculating unit of the next higher order.

The operation is as follows: When the carrying member 27 is in its position of rest with its abutment 45 in contact with the edge 43 of the hole 44, the toothed sector 29 will be engaged by the teeth 30 of the number wheel 24 when the number wheel 24 has been turned to its "5" position. Upon further rotation of the number wheel by depression of the keys, the number wheel will therefore cause the carrying member 27 to be rotated in a clockwise direction against the action of the spring 31 which is thereby strained or wound up, the teeth 30 preventing the toothed sector 29 and thereby the carrying member 27 from returning to its neutral position under the influence of the spring 31.

Figs. 1 and 2 show the number wheel in the zero position immediately after the carrying member has been fully released for return movement. It will be understood that in the zero position the tooth 30d has just left hold of the tooth 29d thus permitting the carrying member 27 to be rotated in an anticlockwise direction under the influence of its spring 31. However, as will be apparent from the above description of the transfer lock, this rotation of the carrying member may take place only after the key, the depression of which caused the number wheel to be rotated to the zero position, has been restored to normal as shown, because as long as this is not the case the detent 38 will engage behind the shoulder 39 and detain the carrying member 27 in the position shown.

When the carrying member 27 is turned in an anticlockwise direction under the influence of its spring 31, it will effect a carry transfer to the numerical group of the next higher denomination by means of the above named pawl, not shown, exactly similar to the pawl 42'.

No claim is made herein to the 5-0 transfer drive which forms the subject matter of my co-

pending application Serial No. 703,248 filed October 14, 1946, now abandoned, or to the staggered tooth transfer drive forming the subject matter of my copending application Serial No. 703,249, filed October 14, 1946, now Patent No. 2,499,946.

Having now particularly described and ascertained the nature of my invention and in what manner the same is to be performed I declare that what I claim is:

- 5 10 In five-key calculating machines, a number wheel of lower order, a set of five keys of lower order cooperating with said number wheel for rotation thereof on depression of any one of said keys, a spring biased transfer member operatively associated with said number wheel of lower order to be moved thereby during part of a revolution of said number wheel and thereafter released to perform a return stroke, a transfer lock individual to said set of keys of lower order and movable on depression of any of said keys of lower order to a position to engage with said transfer member to prevent return movement thereof and on the substantially complete return movement of said keys of lower order said lock being movable to a position to permit the return stroke of said transfer member, a number wheel of higher order, and means associated with said transfer member for imparting transfer motion to said number wheel of higher order from said transfer member during 15 20 25 30 the return stroke thereof.
